CAM OPERATED TIMING MECHANISM

Ralph L. Berg, Crystal Lake, Ill., assignor to Controls Company of America, Schiller Park, Ill., a corporation of Delaware

Filed July 20, 1962, Ser. No. 211,359

10 Claims. (Cl. 200—38)

This invention relates to motor driven timers of the type which operate a function switch at the end of a preset time period. These timers are generally used to perform a single predetermined function at the end of a preset time period such as starting or stopping the operation of an electric appliance.

The primary object of this invention is to provide a means for manually selecting different functions to be performed by the timer at the end of the selected time period.

Timers of this type generally have a switch which is actuated at the end of a predetermined time interval. An adjustable limit stop is positioned in the switch to limit the movement of the switch blade in one direction or the other so that it operates either as an off-on or on-off switch. The advantages of such a system are best shown by the following example. In operating a home air conditioner, it is desirable to have the air conditioner turned on some time before you arrive at home and turned off after you have retired. The present timer can be set to run for a predetermined period of time and to then turn on the air conditioner before you arrive at home. On arrival at home the timer can be reset to turn off the air conditioner after you retire. Most timers can accomplish one or the other of these functions but with this timer it is possible to accomplish both of these functions.

Other objects and advantages will be pointed out in or be apparent from the specification and claims, as will obvious modifications of the single embodiment shown in the drawings, in which:

FIG. 1 is a schematic diagram of the timer and the circuit controlled thereby;

FIG. 2 is an end view of the timer with the cover removed;

FIG. 3 is a view similar to FIG. 2 showing an alternate position for the selector cam;

FIG. 4 is a view taken on line 4—4 of FIG. 2 showing the selector and friction clutch arrangement; and

FIG. 5 is a side view partly broken away showing the timer motor drive.

Referring more particularly to the circuit diagram, FIG. 1, a timing motor 10 is shown connected to drive cam 12 through friction clutch 14. The cam is manually set by turning selector knob 16 in either direction to the desired time interval. On turning the cam, cam follower 18 on switch blade 20 will be cammed out of notch 22 in the cam closing the switch blade with secondary switch blade 24. This will energize the timer motor circuit, that is, from L₁ to L₂ through switch blade 20, secondary blade 24, and line 26. The energization of electrical appliance 28 connected in line 30 will depend on the position of manual selector segment 32.

If the selector segment is in the "off" position and the cam is set to operate for a preselected interval switch blade 20 will be cammed into engagement with contact 34 closing appliance circuit 30 connected between L₁ and L₂.

2

The electrical appliance will then be on for the time period selected. The switch blade will also be cammed into engagement with secondary blade 24 closing the timing motor circuit. At the end of the time period, cam follower 18 will drop into notch 22 opening the switch blade with secondary blade 24 and contact 34. The switch blade will engage limit stop 36 on the selector segment preventing its closure with contact 38 and both circuits will now be open.

If the selector segment is in the "on" position and the timer is turned to the desired time interval, switch blade 20 will be cammed into engagement with stop 40 on the segment opening the appliance circuit. The switch blade will close with secondary blade 24 closing the timing motor circuit. The electrical appliance will now be "off" for the interval of time set on the timer and will be turned "on" at the end of the selected time period when cam follower 18 drops into notch 22.

The timer shown in FIG. 5 has timer motor 10 mounted on housing 42. A gear train (not shown) is provided in the enlarged portion of the timer motor housing with drive shaft 43 extending into housing 42 through bearing 45. Worm gear 44 is mounted on the end of the drive shaft and drives gear 46 on shaft 48 (FIG. 2) which is journaled in bearings 50. A second worm gear 52 is mounted on shaft 48 to engage and drive gear 51 which is freely rotatable on cam shaft 54 (FIG. 4). The rotary motion of gear 51 is transmitted to the cam shaft by friction clutch 14 which is squeezed between gear 51 and lost motion arbor 58. The friction clutch is connected to the arbor by means of a finger 60 which extends into a notch 62 on the arbor. Timing cam 12 is mounted to rotate freely on the arbor and is held thereon by nut 63. The timing cam is limited in its movement by dog 64 on the lost motion arbor which extends into notch 22 in the cam. When cam follower 18 drops into notch 22 the cam will be free to move independently of the shaft within the limits of notch 22 thereby providing a snap action in the switch operation.

In operation, selector knob 16 mounted on the end of the cam shaft is turned to rotate the cam to the desired time setting. On turning the knob, the timing cam will be cammed upward against secondary blade 24 and either limit stop 40 or contact 34 depending on the position of selector segment 32. The timer motor will be energized when blade 20 engages blade 24 and will drive the timing cam back to the starting point. When cam follower 18 drops into notch 22 in the cam, it will force the timing cam ahead at a faster rate than the cam shaft through the camming action of the cam follower on notch 22 providing a snap action in the movement of the switch blade into or out of engagement with the contacts.

Segment 32 is secured to shaft 66 and is rotated from an "on" position to an "off" position by means of a selector knob 68. In the position shown in FIGS. 1 and 2, the segment is in the "off" position since the appliance circuit is opened at the end of the selected time interval. In FIG. 3 the selector segment is shown turned to the "on" position with the switch blade in contact with contact 38 when the cam follower drops into notch 22.

Although but one embodiment of the present invention has been illustrated and described, it will be apparent to those skilled in the art that various changes and modifica-

tions may be made therein without departing from the spirit of the invention or from the scope of the appended claims.

I claim:

1. A timing device comprising, in combination, 5
a timing motor,
timing cam means connected to and driven by said timing motor,

switch means connected with said cam means and including a switch member movable selectively between two operative closed circuit positions in response to movement of said cam means, said switch member biased toward one of its operative positions and movable against said bias to the other of its operative positions by said cam means,

selector means having a first position in the path of movement of said movable switch member for engagement therewith to limit travel of said movable switch member toward one of its operative positions and a second position in the path of movement of said movable switch member for engagement therewith to limit travel of said movable switch member toward its other operative position,

and means for selectively positioning said selector means in its first and second positions whereby said timing device is adapted to provide off-to-on or on-to-off operation.

2. The timing device of claim 1 wherein said cam means includes a first cam portion for moving said movable switch member against said bias to said other operative switch member position and a second cam portion spaced from said first cam portion transversely with respect to the direction of cam movement for releasing said movable switch member for movement to the said one operative switch member position, said cam portions being relatively spaced in said direction of cam movement to sequentially engage and operate said switch means,

and further including over-running clutch means between said cam means and said timer motor, and means for moving said cam means independently of said timer motor for setting said cam means with respect to said switch blade to achieve a predetermined time interval in operation between said first and second cam portions.

3. The timing device of claim 2 wherein the driving connection between said timing cam and said timer motor includes means providing lost motion therebetween so that transition from said first and second cam portions is not solely dependent on the timer motor but is achieved with a snap action.

4. A timing device comprising, in combination, a timing motor,

a rotatable cam connected to and driven by said cam motor,

a cam following switch blade biased into engagement with the periphery of said cam,

first circuit means arranged for engagement by said switch blade when said switch blade is riding on said cam periphery,

said cam periphery including an operating portion spaced from the remainder of said cam periphery in a radial direction with respect to the axis of rotation of said cam so that said switch blade moves radially of said cam and out of engagement with said first circuit means upon registry with said cam operating portion,

second circuit means arranged for engagement with said switch blade when said switch blade is in registry with said cam operating portion,

a selector member having a first position in the path of movement of said switch blade for engagement therewith to limit travel of said switch blade toward said first circuit means and a second position in the path of movement of said switch blade for engagement

therewith to limit travel of said switch blade toward said second circuit means,
and means for selectively positioning said selector member in its first and second positions.

5. The timing device of claim 4 including a drive shaft connected to and driven by said timing motor,

means mounting said cam freely on and for movement relative to said drive shaft, said mounting means also including means providing a lost motion driving connection between said cam and said drive shaft to provide a driving connection therebetween after a predetermined amount of angular movement of said cam means with respect to said drive shaft.

6. The timing device of claim 5 including third circuit means arranged for engagement with said switch blade when said switch blade is in engagement with said cam periphery, said third circuit means being connected to and energizing said timing motor when engaged by said switch blade.

7. The timing device of claim 5 wherein said switch blade is arranged for engagement with said third circuit means when said switch blade is out of engagement with said operating portion of said cam periphery and said switch blade moves out of engagement with said third circuit means when said switch blade is in registry with said cam operating portion.

8. The timing device of claim 5 wherein said cam operating portion is in the form of a notch in the cam periphery into which said switch blade drops when said notch registers with said switch blade.

9. A timing device comprising, in combination, a timing motor,

a drive shaft connected to and driven by said timing motor,
a generally circular cam freely mounted on said drive shaft to permit relative movement therebetween, lost motion connection means connecting said cam to and for movement with said drive shaft and operative to provide a predetermined amount of angular movement of said cam means with respect to said drive shaft,

a cam following switch blade biased into engagement with the periphery of said cam,

first circuit means arranged for engagement with said switch blade when said switch blade is in engagement with said cam periphery,

said cam including an operating portion spaced radially from said cam periphery so that said switch blade moves radially of said cam means upon registry with said cam operating portion to move said switch blade out of engagement with said first circuit means,

second circuit means arranged for engagement with said switch blade when said switch blade is in registry with said cam operating portion,

third circuit means arranged for engagement with said switch blade when said switch blade is in engagement with and riding on said cam periphery, said third circuit means connected to and controlling energization of said timing motor with the duration of engagement of said switch blade with said cam periphery determining a time interval before registry of said cam operating portion and said switch blade, a selector member having a first position in the path of movement of said switch blade for engagement therewith to limit travel of said switch blade toward said first circuit means and a second position in the path of movement of said switch blade for engagement

therewith to limit travel of said switch blade toward said second circuit means, said selector member in both its first and second positions permitting sufficient movement of said switch blade for engagement with said third circuit means, and means for selectively positioning said selector member in its first and second positions.

10. The timing device of claim 9 wherein said cam operating portion comprises a notch arranged for registry with and to receive said switch blade to permit movement of said switch blade into engagement with said second circuit means,

and lost motion connection means connecting said cam to and for movement with said drive shaft and operative to provide a predetermined amount of angular movement of said cam means with respect to said drive shaft.
